CASING FOR UNITARY HEARING AIDS

Don H. Young, West Hempstead, N. Y., assignor
to Dictograph Products Company, Inc., New
York, N. Y., a corporation of Delaware

Application October 31, 1946, Serial No. 706,827

1 Claim. (Cl. 179—107)

1

This invention relates to improvements in hearing aid devices, and it relates particularly to casings for receiving all of the elements of the device, except the ear or head-phone.

Hearing aid devices include a microphone, an amplifying unit, and in most of the prior devices, a separate battery container of substantial size.

Recently, miniature electronic tubes and miniature batteries for energizing such tubes have been produced and have made possible the further substantial reduction in the size of hearing aid devices. These batteries and the tubes are of such small size that the microphone, the amplifier, and the batteries can be housed in a single container of about the same size as the microphone and amplifier units manufactured heretofore.

These unitary hearing aid devices, while very convenient for the wearer and relatively inconspicuous, are difficult to assemble and service for the reason that the amplifier must be assembled in a much smaller space than was available heretofore, with the result that the soldering of the various connections, and the orderly arrangement of the various parts is very difficult. Moreover, because of the limited space available, access to the batteries, tubes and other elements for replacement or repair can be had only with great difficulty.

In accordance with the present invention, the various elements of a hearing aid device are assembled in a chassis which is constructed to receive all of the elements in predetermined positions and with adequate provisions made for the wires and conductors necessary for the device.

More particularly, the casing may include a chassis block or skeleton framework which is provided with recesses and openings into which the various elements of the amplifier, the microphone and the batteries fit, and which include channels and openings in convenient positions for receiving the conductors, resistors and condenser that are required in the amplifier circuit. Inasmuch as all of the elements of the device can be assembled in the casing in predetermined positions, the assembly and servicing of the device are greatly facilitated.

The chassis block preferably is formed of a synthetic plastic and may be provided with suitable cover portions for concealing the various elements mounted in the block. The cover portions may take the form of removable plates which are suitably perforated in front of the microphone, and, if desired, near the tubes for

2

ventilation; or the chassis block with its attached elements may be covered by means of a removable pouch. The use of a pouch or similar removable cover makes possible easy change in the appearance of the device to conform with the clothing of the wearer. Thus, the pouch or casing may be made of fabric, leather or simulated leather of suitable design or color to blend or contrast with the costume of the user.

For a better understanding of the present invention, reference may be had to the accompanying drawings, in which:

Fig. 1 is a perspective view of a typical form of chassis block embodying the present invention with the microphone, on-and-off switch and volume control, tone control and other elements shown assembled in the block;

Fig. 2 is a perspective view of the back of the chassis block illustrating the electronic tubes and the batteries mounted in the block;

Fig. 3 is an exploded perspective view of the chassis block with the elements of the hearing aid device removed therefrom;

Fig. 4 is a perspective view of the hearing aid device having cover plates thereon; and,

Fig. 5 is a schematic diagram showing electrical connections to certain fastening bolts.

The form of the invention chosen for purposes of illustration may include a chassis block member 10 which may be made of any suitable material such as, for example, a moldable synthetic resin, wood, or other material, preferably having insulating properties. The chassis block 10 illustrated is slightly over four inches in length, by two and one-fourth inches in width, and approximately five-eighth of an inch thick. The dimensions of the block can be varied but the block should be sufficiently small so that it can be worn relatively inconspicuously on the clothing or in a vest or shirt pocket.

The hearing aid device includes the usual microphone 11, an on-off switch and volume control 12, and a tone control rheostat 13, all of conventional construction. The electronic amplifier may include a plurality of miniature vacuum or electronic tubes 14, 15, and 16, providing a three-stage amplifier which is capable of supplying a sufficient output for all purposes. In order to energize the tubes, it is necessary to provide the usual "A" battery 17, "B" battery 18, and "C" battery 19, as well as a transformer 20 and one or more resistors 21 and condensers 22 in order to complete the amplifier circuit. In addition to the elements enumerated above, conductors or wiring between the various elements are provided,

but not illustrated inasmuch as they are conventional and do not form a part of the present invention.

In the unitary type of device illustrated in the drawings, haphazard arrangement of wiring and elements of the prior devices is eliminated and each element occupies a pre-selected place with respect to the other elements. The chassis block 10 is constructed in such a way that all of the elements fit within the recesses provided in the block 10 and at the same time are spaced apart so that the wiring of the device will lie within the periphery of the block.

Referring now to Figs. 1 and 3, the chassis block 10 may be provided at the end with a pair of generally circular recesses 23 and 24 which open through the face 25 of the block and through its end 26. The recesses 23 and 24 are adapted to receive the switch and volume control 12 and the tone control 13 so that portions of their knurled peripheries are accessible for operation.

Immediately to the rear of the recesses 23 and 24 is a larger recess 27 defined by a generally annular rim 28 and disk-like base 28a within which is mounted the microphone 11. It should be noted that the rim 28 is interrupted adjacent to the recesses 23 and 24 so that conductors may extend between these various recesses.

Adjacent to the recess 27 is a generally rectangular opening 29 for receiving the transformer 20. The transformer may be cemented in the recess or secured therein in any desired way.

On or about the same plane as the transformer recess 29 is a circular recess 30 in which is mounted the "C" bias-battery 19.

Referring now to Fig. 2, which discloses the back of the chassis block 10, it will be seen that the upper end of the block is provided with a series of three recesses 31, 32, and 33 extending transversely of the chassis 10 and separated by disconnected partition elements 34 and 35 that extend inwardly from the periphery of the chassis block 10. These disconnected partitions, in addition to separating the recesses for the tubes 14, 15, and 16, act to reenforce the rim member 28 and disk member 28a inasmuch as the partitions 34 and 35 extend across apertures 36 and 37 on opposite sides of the microphone recess. The apertures 36 and 37 receive wires and the resistors and condensers 21 and 22.

Instead of mounting individual units in separate recesses, it may be found advantageous to mount several like units in the same recess, such as the tubes 14, 15 and 16, for example, which may be mounted together in one recess, such as 31, in which case partitions 34 and 35 will be omitted to make one larger recess.

The batteries 17 and 18 are housed in the lower end of the chassis block 10 in suitable recesses 38 and 39, respectively, which closely fit the batteries so as to hold them against displacement. Suitable channels 40 and 41 may extend from the recesses 38 and 39 into the transverse recess 33 for receiving wires for connecting the batteries to the tubes and other elements. The chassis block 10 therefore forms a skeleton framework for receiving all of the elements of the hearing aid in predetermined positions.

While the chassis block 10 may be made up of one element, it is preferred to separate the block into two parts 10a and 10b, one of which receives the batteries and the other of which receives the amplifier and microphone. This arrangement allows for a change in the battery section so that batteries of a different type and voltage may be

used for special purposes. However, the batteries may be replaced without removing the end section of the casing, but by displacing a movable section over the batteries, this movable section being the lower half of the back cover, to be described.

Referring now to Fig. 3, the end section 10a may be provided with a tongue member 42 which is adapted to fit into a groove 43 in the section 10b as shown in Fig. 2 and to be secured thereto by means of suitable bolts 44. The amplifier and microphone section 10b may also be provided with a suitable tongue 45 which engages in a groove or recess 46 in the section 10a and may be detachably connected therewith by means of a bolt 47.

The bolts 44, 44' and 47 may serve to electrically connect the battery section with the amplifier section, as by connecting middle bolt 44' to the common terminals of the batteries 17 and 18, and outer bolts 44 and 47 to the other terminals of corresponding batteries 18 and 17, the amplified units then being connected to these bolts, as shown in Fig. 5.

The casing for the batteries and amplifier may be completed by applying thereto suitable cover plates 48 and 49. As illustrated in Fig. 4, the plates 48 and 49 may consist of flat sheets of plastic or other material which are secured by means of screws 51 to the chassis block 10. The plate 48 may be provided with a grille 52 overlying the microphone, and the back plate 49 is preferably divided and hinged at 53 so as to provide a movable cover 49' over the battery section to facilitate battery installation and replacement. The cover 49' may be provided with tongues 54 embracing the edges of the block 10 so as to hold it in closed position. Alternatively, the plate 49 may be provided with an access opening closed by a separate movable cover.

It will be observed that no separate casing is required for the instrument, the blocks 10a and 10b and the plates 48 and 49 serving in lieu thereof, i. e., the edges of the block are finished and, with plates 48 and 49, serve as both chassis frame and casing.

The unit illustrated in Fig. 4 may, if desired, be provided with suitable surface ornamentation and a clip, not shown, on the back plate 49 for attaching the device to the clothing. Alternatively, the entire unit may be slipped inside of a pouch formed of leather, fabric or other suitable material in order to render it less conspicuous or more attractive. Moreover, if desired, the front and back plates 48 and 49 may be omitted and the chassis block 10 can be housed in the pouch or casing formed of leather or other material which conceals and protects the elements.

In either case, the overall size of the device will not be appreciably altered and the entire unit may be readily carried on the clothing or in a vest or shirt pocket. The only other element required for the device is the usual receiver which may be connected with the amplifier through suitable plugs and sockets, not shown.

It will be understood that the device is susceptible to considerable modification in the arrangement and size of the parts and that the type of amplifier and microphone used therein may be modified, as desired. Therefore, the form of the invention described above should be considered as illustrative of the invention and not as limiting the scope of the following claim.

I claim:

A case for supporting elements of an electronic tube hearing aid, including the microphone, "A," "B" and "C" batteries, tubes, transformer, as-

sociated elements and wiring of an electronic hearing aid device, comprising a first block-like portion, a second block-like portion, means detachably connecting said portions in end-to-end relation to form a generally rectangular block-like member, means forming recesses in said first block-like portion receiving and substantially fitting said "A" and "B" batteries, means forming recesses in said second block-like portion receiving said "C" batteries, microphone, tubes, associated elements and a part of said wiring, and aligned channels in both of said block-like portions receiving wiring for connecting said batteries to the elements in said second block-like portion, and cover portions secured to and overlying said recesses in said block-like member.
